United States Patent Office

Des. 204,073
Patented Mar. 15, 1966

204,073

SERVING DISH

Robert E. Lovett and Glenna B. Lovett, both of 1286 Sierra Madre Blvd., San Marino, Calif.

Filed Aug. 2, 1965, Ser. No. 86,380

Term of patent 14 years

(Cl. D44—10)

FIG. 4.

FIG. 1 is a top plan view of a serving dish showing our new design;

FIG. 2 is a front elevational view;

FIG. 3 is a sectional view on the line 3—3 of FIG. 1; and

FIG. 4 is an end elevational view taken from the right of FIG. 1.

We claim:

The ornamental design for a serving dish, as shown.
